AUTOMATIC INDICATING SYSTEM

William J. Phillips, North Kansas City, and
Raleigh Scovel, Kansas City, Mo.Application July 29, 1936, Serial No. 93,220
Renewed February 16, 1939

8 Claims. (Cl. 179—5)

This invention relates to electrical alarm systems generally, and more specifically to automatic fire and burglar alarms of the character that employs a part of a telephone system having a dialing instrument and an annunciator.

The primary object of this invention is to provide, in combination with a telephone system of the aforementioned type, mechanism operable by some act to be detected that will actuate the annunciator to reveal the location of the act being detected.

Another important aim of this invention is to provide, in an automatic indicating system, a relay that may be connected directly to the circuit of said indicating system in such fashion as to open and close the circuit at predetermined intervals.

A still further object of this invention is to provide an automatic indicating system, having as a part thereof, a relay comprising in the main, a specially formed circuit making and breaking disc, and unique means for rotating said disc upon the closing of a second circuit which has a switch element therein that closes when some act 25 to be detected effects it.

A yet further object of the invention is the provision of a relay for automatic indicating systems, that is efficient, compact, cheap to manufacture, and designed without complicated parts, to the end that it may be interposed in automatic telephone circuits or placed in an individual circuit so that a conventional type annunciator may be operated through the opening and closing of the main circuit having parts of 30 the relay therein.

An exceptionally large number of minor objects will appear during the course of the following specification, referring to the accompanying drawings, wherein but one embodiment of the 40 invention is illustrated, and wherein:

Figure 1 is a vertical section through the relay, taken along line I—I of Fig. 2.

Fig. 2 is a cross sectional view, taken along line II—II of Fig. 1.

Fig. 3 is a horizontal, cross sectional view, taken along line III—III of Fig. 1.

Fig. 4 is a fragmentary, side elevation of the relay, with a part of the side wall broken away 50 to reveal parts therebeneath.

Fig. 5 is a diagrammatical view of the disc and two switches.

Fig. 6 is a fragmentary, sectional view through the disc, taken on line VI—VI of Fig. 2, and,

Fig. 7 is a wiring diagram illustrating the

switch-operating and latch-operating parts of the relay.

The term "relay" throughout the specification is used to indicate the impulse sending mechanism and associated parts illustrated in detail in Figs. 1, 2 and 3. This relay may be attached in circuit with the ordinary mechanical telephone line so that the conventional annunciator that is operated when the well known dialing instrument is manipulated will be actuated.

Obviously, when attaching the relay in circuit with the automatic telephone system, it is located between the dialing instrument and the annunciator, preferably in the building where the dialing instrument is located, so that when the 15 second circuit is associated with the relay, it will indicate the location of the act to be detected by revealing at the annunciator, the telephone number at the place where the relay is installed. It is conceivable, of course, that the relay may be 20 installed where desired and a separate circuit used which has no relation to a telephone system or any other known electrical device.

In the last mentioned instance, an annunciator may be located at the police department or fire 25 department and the first part of the movement of the disc will be effective in "calling" the department desired. The last part of the movement of the disc will operate the annunciator at the particular department so as to reveal to the 30 attendant, either the telephone number of the scene of trouble, or another number, such as street number or a code number that will reveal to the attendant the exact location of the act being detected.

Referring to the relay per se, which, as aforementioned, may be electrically connected to a separate circuit leading to an annunciator, not here shown, the same comprises a suitable housing 8, in the form of a metallic box or the like, 40 having a partial partition 10 therein, made of insulating material such as fiber. This partition 10 journals one end of winding stem 12 and one end of shaft 14 that form a part of the motivating structure built in the relay.

A spring 16, having one end attached to a fixed element as at 18, and the other end secured to winding stem 12 as at 20, may have energy stored therein when stem 12 is rotated to wind spring 16 tightly thereabout. A train of gears, 50 similar to that found in conventional clockwork, is associated with spring 16. These gears comprise a first gear 22, keyed to stem 12 and in mesh with a second gear 24, loosely mounted upon a shaft 26. This second gear carries a pawl 28 55

that is yieldably pressed against ratchet 30 by spring 32. It is through this ratchet and pawl that second gear 24 is caused to rotate shaft 26 during the actual operation of the relay, but is precluded from rotating shaft 26 while spring 16 is being wound. In other words, when spring 16 is being wound around stem 12, second gear 24 rotates freely upon shaft 26, but when gear 22 exerts force to rotate second gear 24 in the opposite direction, pawl 28 will be effective in transmitting that force to shaft 26.

A third gear 34 is keyed to shaft 26 and is in mesh with pinion 36, which in turn is keyed to shaft 14. An escapement gear 38, carried by shaft 26, co-operates with the escapement yoke 40 and its depending pendulum 42 in governing the speed of the intermeshing gears when spring 16 is serving to motivate the same. Yoke 40 has a depending stem 44 that is in screw-threaded engagement with weight or pendulum 42 so that the length of the stroke might be varied to suit conditions.

Third gear 34 is provided with a laterally extending ear 46 which engages dog 48, pivotally mounted upon pintle 50. This pintle and dog is supported by a bracket 52 that extends upwardly from the bottom of housing 8, and said bracket is formed to present a pair of stops 54 and 56 respectively.

30 An electro-magnet 58 is disposed within housing 8 and actuates pivotally mounted armature 60 when energized. This armature 60 is associated with dog 48 so that it will swing the same around its pivotal support under certain conditions. Shaft 26 extends transversely across housing 8 and supports the circuit making and breaking disc 62, which has notches 64 provided therein for the reception of the curved end 66 of contact finger 68. As will be later mentioned, when 40 contact finger 68 enters any one of the several notches 64 formed in the periphery of disc 62, contact point 70 will leave contact point 72 carried by a companion finger 74, and thereby break a circuit. Fingers 68 and 74 are resilient and 45 mounted upon partial partition 10 in substantially the same plane as the major plane of disc 62.

Another set of contact strips 76 and 78, having contact points 80 and 82, are mounted upon some 50 part of housing 8 and insulated therefrom by a suitable block 84. An elevated cam face 86 projects from the side of disc 62 and engages strip 78 once during a complete revolution of disc 62. When the said strip is so engaged, points 80 and 82 are moved together to close a circuit.

It is conceivable that other means may be built into the aforesaid relay which would cause it to perform the same function as the one just described. Such a relay is interposed in a circuit 60 with the dialing instrument 88 of an automatic telephone system. Wires 90 and 92 join the instrument 88 with an annunciator, not here illustrated, and a supplementary circuit, having means therein for closing the same when an act 65 to be detected is performed, also is contemplated when making a complete installation.

In the instance illustrated, switch points 94 and 96 are held open by a fusible link 98, which 70 will release upon being subjected to a high temperature, such as when a fire occurs. This action will, of course, close points 94 and 96, but if a burglar alarm is to form a part of the indicating system, the means for closing switch points 75 94 and 96 may be mechanical ones, operated upon

manual manipulation of a window, door, or the like.

Referring to Fig. 7, it will be obvious that wires 90 and 92 are joined to the above described parts of the relay and one of the circuits, including the points 94 and 96 that are closed by releasable member 98, serves as the switch or analogous device which is actuated when an act to be detected is performed. When this switch or contact points 94 and 96 are closed, electro-magnet 10 58 will be energized to release the mechanical parts of the relay by attracting armature 60. When armature 60 is attracted, it will be drawn against electro-magnet 58, will swing dog 48 about pintle 50, and withdraw the dog from engagement with ear 46. When such action occurs, spring 16 may exert its force to rotate disc 62 about its axis of rotation of shaft 26.

The circuit which is closed by the bringing together of points 94 and 96 may be traced as follows: wire 92, wire 100, wire 102, wire 104, electro-magnet 58, wire 106, contact points 82 and 80 of strips 78 and 76 respectively, wire 108, and wire 110 to line wire 90.

Manifestly, as soon as disc 62 starts to rotate 25 in the direction of the arrows shown in Figs. 1, 5 and 7, contact points 80 and 82 will spring apart to open the circuit just traced, and thereby de-energize electro-magnet 58; such de-energization will permit the weighted portion of dog 48 30 to carry armature 60 back to the point of beginning and to further dispose the end of dog 48 in the path of travel of ear 46.

As disc 62 is rotating, however, contact points 70 and 72 are being intermittently brought together so that the annunciator circuit, of which wires 90 and 92 are a part, will be made and broken to transmit impulses indicating a call and a location, all in accordance with the number of notches 64 formed in disc 62. When the end 66 40 of finger 68 drops below the normal annular plane of disc 62, the circuit is opened, and it is this mechanical act that causes the annunciator to function. The circuit which is opened and closed by the bringing together of contact points 70 and 72 and during the time disc 62 is rotating may 45 be traced as follows: Wire 92, wire 100, closed points 94 and 96, wire 102, wire 112, contact finger 68, closed points 70 and 72, contact finger 74, wire 114, and wire 110 to line wire 90.

When disc 62 has made one complete revolution, ear 46 will again engage dog 48 at precisely the same time contact points 80 and 82 are moved together by elevated cam face 86. Thus the signal will be repeated so long as contact points 55 94 and 96 remain together.

As has been mentioned before, wires 90 and 92 may lead directly to an annunciator installed for the specific purpose of functioning with the relay and circuits herein described. The combination, 60 however, is a novel one and installing the indicating system in stations equipped with mechanical telephones of the well known automatic type eliminates the necessity of special outside wiring and provides inexpensive means of presenting an 65 efficient alarm.

Having thus described the invention, what is claimed as new and desired to be secured by Letters Patent is:

1. In an automatic indicating system, having 70 an annunciator, impulse sending mechanism in circuit with the annunciator comprising a circuit making and breaking disc, having a series of notches formed in the periphery thereof; a switch in said circuit having a part thereof in follow- 75

- ing engagement with the periphery of the disc to intermittently open and close the said circuit; means for rotating the disc about its axis; a latch to normally hold the rotating means inactive; 5 an electro-magnet for moving the latch to release the rotating means; and a circuit having a switch therein for energizing the electro-magnet, said last mentioned switch being held closed when the latch is holding the rotating means inactive.
2. In an automatic indicating system, having an annunciator, impulse sending mechanism in circuit with the annunciator comprising a circuit making and breaking disc, having a series of notches formed in the periphery thereof; a switch 10 in said circuit having a part thereof in following engagement with the periphery of the disc to intermittently open and close the said circuit; means for rotating the disc about its axis; a latch to normally hold the rotating means inactive; an 15 electro-magnet for moving the latch to release the rotating means; a circuit, having a switch therein, for energizing the electro-magnet; and a cam face on the side of said disc for periodically closing the last mentioned switch as the disc 20 is rotated.
3. In an automatic indicating system, having an annunciator, impulse sending mechanism in circuit with the annunciator comprising a circuit making and breaking disc, having a series of notches formed in the periphery thereof; a switch 25 in said circuit having a part thereof in following engagement with the periphery of the disc to intermittently open and close the said circuit; means for rotating the disc about its axis; a latch to normally hold the rotating means inactive; an 30 electro-magnet for moving the latch to release the rotating means; a circuit, having a switch therein, for energizing the electro-magnet; and a cam face on the side of said disc for periodically closing the last mentioned switch as the disc 35 is rotated, said last mentioned switch being closed once during each complete revolution of the said disc.
4. In an automatic indicating system, having an annunciator and a switch closable by the act 40 to be indicated, impulse sending mechanism in circuit with both the annunciator and said switch comprising a rotatable circuit making and breaking disc provided with notches in the periphery thereof; a second switch operable by the notches 45 in the disc when the same is rotated to intermittently open and close the said circuit; a spring for rotating the disc; a gear train for transmitting driving power from the spring to the disc; a dog 50 movable to and from a position against one of the gears to preclude movement thereof; an electromagnet for so moving the dog; and a third switch movable to and from a circuit closing position by the rotation of said disc, said electro- 55 magnet being in the circuit with the first mentioned and third switch.
5. In an automatic indicating system, having an annunciator and a switch closable by the act 60 to be indicated, impulse sending mechanism in circuit with both the annunciator and said switch comprising a rotatable circuit making and breaking disc provided with notches in the periphery thereof; a second switch operable by the notches 65 in the disc when the same is rotated to intermittently open and close the said circuit; a spring for rotating the disc; a gear train for transmitting driving power from the spring to the disc; a dog 70 movable to and from a position against one of the gears to preclude movement thereof; an elec- 75 tro-magnet for so moving the dog; and a third switch being in circuit with the first mentioned switch.
6. In an automatic indicating system, having an annunciator and a switch closable by the act 80 to be indicated, impulse sending mechanism in circuit with both the annunciator and said switch comprising a rotatable circuit making and breaking disc provided with notches in the periphery thereof; a second switch operable by the notches 85 in the disc when the same is rotated to intermittently open and close the said circuit; a spring for rotating the disc; a gear train for transmitting driving power from the spring to the disc; a dog 90 movable to and from a position against one of the gears to preclude movement thereof; an electro-magnet for so moving the dog; and a third switch movable to and from a circuit closing position by the rotation of said disc, said electro- 95 magnet being in the circuit with the first mentioned and third switch, said second switch being in circuit with the first mentioned switch.
7. In an automatic indicating system, having an annunciator and a switch closable by the act 100 to be indicated, impulse sending mechanism in circuit with both the annunciator and said switch comprising a rotatable circuit making and breaking disc provided with notches in the periphery thereof; a second switch operable by the notches 105 in the disc when the same is rotated to intermittently open and close the said circuit; a spring for rotating the disc; a gear train for transmitting driving power from the spring to the disc; a dog 110 movable to and from a position against one of the gears to preclude movement thereof; an electro-magnet for so moving the dog; and a third switch movable to and from a circuit closing position by the rotation of said disc, said electro- 115 magnet being in the circuit with the first mentioned and third switch, said second switch being in circuit with the first mentioned switch.
8. In an automatic indicating system, having an annunciator and a switch closable by the act 120 to be indicated, impulse sending mechanism in circuit with both the annunciator and said switch comprising a rotatable circuit making and breaking disc provided with notches in the periphery thereof; a second switch operable by the said 125 disc to intermittently open and close the circuit when the same is rotated, and normally maintaining the circuit in an open condition; a spring for rotating the disc; a gear train for transmitting driving power from the spring to the disc; a gravity held dog movable from a normal position 130 against one of the gears to preclude movement of the train of gears and said disc; an electro- 135 magnet in circuit with and energized when the first mentioned switch is closed to overcome the action of gravity on the dog to move the same from engagement with one of the gears; and a third switch normally maintained closed by the disc and forming a part of the normally open circuit, said third switch being opened by the movement of the disc as the latter rotates to intermittently close the said second switch.
